CLAIM

The ornamental design for a housing for a lighting ballast, as shown and described.

DESCRIPTION

FIG. 1 is a left front perspective view depicting a housing for a lighting ballast;

FIG. 2 is a right rear perspective view depicting the housing of FIG. 1;

FIG. 3 is a right side elevational view depicting the housing of FIG. 1;

FIG. 4 is a left side elevational view depicting the housing of FIG. 1;

FIG. 5 is a front elevational view depicting the housing of FIG. 1;

FIG. 6 is a rear elevational view depicting the housing of FIG. 1;

FIG. 7 is a top plan view depicting the housing of FIG. 1; and,

FIG. 8 is a bottom plan view depicting the housing of FIG. 1.

The details shown in broken lines in the figures form no part of the claimed design of a housing for a lighting ballast. The surface shading shown in the figures represents contour and not surface ornamentation.
